TEMPERATURE CONTROL IN REFRIGERATING OR COOLING APPARATUS

John Furse Bancroft Vidal, Purley, England, assignor to J. Stone & Company, Limited, Deptford, England, a company of Great Britain

Application April 21, 1938, Serial No. 203,428
In Great Britain April 22, 1937

4 Claims. (Cl. 62—91.5)

This invention comprises improvements in and connected with temperature control in refrigerating or cooling apparatus and particularly in refrigerator chambers adapted for use in vehicles, railway carriages, vans and the like.

5 The principal object of the present invention is to improve automatically controlled refrigerator installations which are self-contained and which dispense with the employment of any outside or auxiliary power means for the operation 10 of the control devices.

In these installations a refrigerant container 15 is arranged in a heavily insulated box or chamber having controlled communication with the cold storage space, such communication being regulated or shut-off by shutters, doors or other valve-like means. The partial or complete closing of such shutters has the effect of reducing or 20 stopping the circulation of relatively warm air from the cold storage chamber past the refrigerant container, thereby slowing down or arresting the evaporation of the refrigerant.

Apparatus for temperature control according 25 to this invention comprises a container for vaporizable refrigerant and adapted for withstanding pressure, a diaphragm or bellows device 30 adapted for being flexed by pressure admitted from the container, temperature-responsive means operative for controlling pressure admission to the diaphragm or bellows device, and a shutter device operatively connected with the diaphragm or bellows and effective for regulating air circulation past the container.

In order to enable the invention to be readily 35 understood reference is made to the accompanying drawings, wherein:

Figure 1 is a more or less diagrammatic cross 40 sectional view of a vehicle body fitted with one example of refrigerating apparatus in accordance with these improvements.

Figure 2 is a diagrammatic representation of another example.

Figure 3 is a longitudinal sectional elevation 45 of the roof of a railway vehicle fitted with refrigerating apparatus similar to that seen in Figure 2.

Figure 4 is a cross section of Figure 3.

Figure 5 is a sectional elevation to a larger 50 scale of the pressure device and linkage seen in Figure 3.

Referring to Figure 1, *a* represents a cold storage chamber or insulated vehicle body and *b* a heavily insulated compartment at one side or end of such chamber or body. The compartment *b* has a relatively large opening at the bot-

tom communicating with the cold storage chamber *a* and in this opening are fitted louvre shutters *c* or other suitable doors or valves. The compartment *b* also has a relatively small opening *d* at the top communicating with the top space of the cold storage chamber *a*. Within the chamber *b* is suitably supported a CO₂ container *e* which is preferably provided with heat exchange fins or the like and is hermetically closed and adapted for withstanding low pressures. It is provided with a blow-off valve *f* which may be adjusted to limit the pressure in the container *e* say to about five pounds per square inch. A gas pipe *g* is led from the container to a heat exchange device *h*, such as a coil, disposed externally of the cold storage chamber *a* and serving as a pre-heater. From the coil *h* a gas pipe *j* passes to a suitable power element which may take the form of an expandible diaphragm or bellows device *k* which is appropriately linked with the louvre shutters *c* for operating the latter. In the pipe *j* there is a valve at *l* in operative connection with a thermostat *m* disposed within the cold storage chamber *a*. The thermostat *m* may be a bulb containing a suitable fluid and the valve at *l* may be a needle valve operatively connected with a diaphragm or piston under the influence of pressure changes due to expansion and contraction of the fluid in the bulb *m*. The diaphragm device *k* is fitted with a restricted leakage vent which may take the form of a small tube fitted with a valve *k'*, the last named being adjusted to permit of a suitable rate of pressure leakage from the diaphragm chamber.

The operation will now be apparent. The storage chamber *a* having been closed after the introduction of goods, air will circulate through the cold compartment *b*, the warm air from the chamber *a* entering at *d* and descending, upon being cooled by the CO₂ container *e*, so that an outflow of cold air from *b* to *a* past the open louvres *c* is effected. The heat exchange between such air and the container *e* causes evaporation of the CO₂ so that a pressure is developed within the container, such pressure being limited by the blow-off valve *f*. When the circulation of cold air has reduced the temperature within the storage chamber *a* to the desired degree, the thermostat *m* produces an opening of the valve at *l* so that pressure gas passes to the power element *k* which thereupon operates to move the shutters *c* towards the closed position, thereby throttling the circulation and reducing the rate of evaporation in the container *e*. The

valve l and power element k cannot be hindered in operation by freezing or condensation, because the gas has been warmed in the preheater coil h before passing to them. When the temperature has been reduced to a value within the prescribed limits, the thermostat m may produce a complete closure of the shutters c so that circulation of cold air and evaporation of CO_2 are arrested. In this condition, the top opening d may permit of a little spillage of cold air from time to time from the compartment b into the chamber a . Reverse action of the thermostat may operate to shut off the flow of gas to the pressure device k and to relieve the pressure therein. However, in the example illustrated in Figure 1, the leakage at k^1 , whilst slow enough to maintain an operating pressure in the device k during operation of the latter, is sufficient for exhausting the space behind the diaphragm in reasonable time when the valve at l is closed by the thermostat. In the foregoing it has been assumed that the shutters c are self-opening, as by providing them with spring or gravity means for that purpose, and that pressure is admitted to the device k for closing them. However, the shutters c might equally be self closing and the pressure admitted to the device k for opening them.

The modified arrangement in Figure 2 differs from that in Figure 1 principally in regard to the shutter devices. In Figure 2, the CO_2 container e^1 is a shallow vessel having a shallow V-shaped bottom fitted with heat exchange fins e , this container being fitted in a roof space and fragments of roof fittings being indicated at r and r^1 . The shutters consist of a pair of angle plates c^1 c^2 each plate being mounted on a rock shaft s at the apex of its angle. In the closed condition of the shutters, illustrated in full lines in Figure 2, each plate part c^1 rests against a roof fitting r or r^1 and each plate part c^2 rests against a trough t extending along beneath the container e^1 and adapted for collecting moisture which condenses upon the bottom of the container and runs down to the middle drip point above the trough. The closed container e^1 is connected by a pipe g^1 with a valve casing n , the blow-off valve f being on the pipe g^1 in this case. Admission of gas from the pipe g^1 to the casing n is controlled by a valve o which is operatively connected with a diaphragm or piston device in a chamber n^1 , the last-named being connected by a tube with the thermostat bulb m . The valve casing n is connected by a pipe with the pressure device k , the diaphragm of the latter being connected by a link p with a two-armed lever q . The top arm of the lever q is connected by a link u with the lower arm of a two-armed lever v , the upper arm of this lever being connected with the plate part c^1 of the right hand shutter. The lower arm of the lever q is connected by a link u^1 with the lower arm of a two-armed lever v^1 , the upper arm of this lever being connected with the plate part c^1 of the left hand shutter. When the temperature influencing the bulb m rises, the pressure due to expansion of the fluid becomes operative in the chamber n^1 for opening the valve o . Thereupon, gas is admitted to the device k to dilate the diaphragm thereof. The consequent push on the link p causes the three levers q v and v^1 to be rocked to the dotted line position with the result that the shutters c^1 c^2 are rocked to an open position shown in dotted lines. In this open position, relatively warm air at the roof can pass over the top edges

of the shutters to become cooled in contact with the CO_2 chamber e^1 whereupon this air descends between the bottom edges of the shutters and the trough t , as indicated by the dotted arrows in Figure 2.

Figures 3 and 4 show apparatus similar to that of Figure 2 as it appears when installed in the roof of a vehicle, and in Figure 3 it will be seen that the shallow container e^1 may be of considerable length so that it extends along the roof. The container e^1 may be charged with blocks of CO_2 through hand holes in the roof, these being closable gas-tightly by means of plugs or covers x held down by fastening means x^1 . Figure 4 shows the shafts s supported by brackets y from the roof fittings r r^1 and the trough t , which is drained by a pipe t^1 , suspended by small plates z from the CO_2 container. It will be clear from Figures 3 and 4 that the shutters c^1 c^2 are co-extensive with the container e^1 along the roof, the pressure device k for operating them being shown to the right-hand side of Figure 3 together with the linkage through which it operates, which linkage will be described in detail with reference to Figure 5.

Referring to Figure 5, the left hand shaft s is fitted with an upwardly extending arm 1 and the right hand shaft s is fitted with a downwardly extending arm 2 , the arms 1 and 2 being interconnected by a link 3 of adjustable length. This interconnection ensures simultaneous and opposite turning of the shafts s , as is necessary for producing the movements of the shutters c^1 c^2 already described. The right hand shaft s has fixed to it an arm 4 which has a pin and slot connection with one end of a lever arm 5 , the pin being insertable into any one of a number of holes to provide a range of adjustment. The lever arm 5 is pivotally mounted at its opposite end in a hanger 6 suspended from the pressure device k , the latter being suspended from the roof by brackets 7 . A disc 8 attached to the diaphragm of the pressure device has a boss at its centre which is connected with the lever arm 5 by means of a divided screw threaded rod 9 , the parts of the latter being united by a screw threaded coupling sleeve 10 which can be turned to adjust the length of the rod. Referring to Figures 4 and 5, it will be apparent that dilation of the diaphragm will depress the rod 9 , Figure 5, and the lever arm 5 , thereby turning the right hand shaft s counterclockwise and the left hand shaft s clockwise to effect opening of the shutters c^1 c^2 Figure 4. The operation of the similar apparatus in Figure 2 having already been described, further description of the apparatus in Figures 4 to 6 is thought to be unnecessary.

I claim:

1. Refrigerating or cooling apparatus comprising an evaporative refrigerant container capable of withstanding pressure, a power element having a diaphragm adapted to be flexed by pressure fluid supplied to said element from the container, a pipe connecting said container with said power element, a shut-off valve in said pipe, temperature-responsive means operative on said valve for controlling pressure admission to the power element, and a shutter device operatively connected with the diaphragm of said power element for regulating circulation past the container.

2. Refrigerating or cooling apparatus comprising an evaporative refrigerant container capable of withstanding pressure, a power element having a diaphragm adapted to be flexed by

5 pressure fluid supplied to said element from the container, a pipe connecting said container with said power element, a shut-off valve in said pipe, temperature-responsive means operative on said valve for controlling pressure admission to the power element, said pipe being formed with a heat exchange coil, and a shutter device operatively connected with the diaphragm of the power element for regulating air circulation past the container.

10 3. Refrigerating or cooling apparatus comprising an evaporative refrigerant container capable of withstanding pressure, a leaky power element having a diaphragm adapted to be flexed by pressure admitted from the container, said leak permitting return of the diaphragm to normal when pressure admission is shut off, a pipe connecting said container with said power element, a shut-off valve in said pipe, temperature-responsive means connected to operate said valve

for controlling pressure admission to the power element, and a shutter device operatively connected with the diaphragm of the power element for regulating air circulation past the container.

4. Refrigerating or cooling apparatus comprising an evaporative refrigerant container capable of withstanding pressure, a power element having a diaphragm adapted to be flexed by pressure admitted from the container, a pipe connecting said container with said power element, 5 a shut-off valve in said pipe, temperature-responsive means connected to operate said valve for controlling pressure admission to the power element, a pair of rock shafts, a pair of angle plates each mounted at the apex of its angle on one of said rock shafts respectively, said rock shafts and angle plates being operatively connected with the diaphragm of said power element for regulating air circulation past the container.
